UNITED STATES PATENT OFFICE.

WILLIAM T. SHAFFER, OF EVANSTON, WYOMING.

CLEANER.

1,040,038.

Specification of Letters Patent.

Patented Oct. 1, 1912.

Application filed May 17, 1911. Serial No. 627,802.

To all whom it may concern:

Be it known that I, WILLIAM T. SHAFFER, a citizen of the United States, residing at Evanston, in the county of Uinta and State of Wyoming, have invented certain new and useful Improvements in Cleaners; and I do declare the following to be a full, clear, and exact description of the invention, such as will enable others skilled in the art to 10 which it appertains to make and use the same.

This invention relates to pneumatic cleaners, and more especially to those that employ a rotary brush or head for sweeping 15 or a suction nozzle or head for dusting; and the object of the same is to produce various improvements in a machine of this character.

To this end the invention consists in 20 certain improvements in the dust receptacle, and in other features as will appear in the following specification and claims, and as shown in the drawings wherein—

Figure 1 is a side elevation of this machine complete. Fig. 2 is a central longitudinal section. Fig. 3 is a plan view. Fig. 4 is a rear elevation. Fig. 5 is a bottom plan view of the closure for the passage between the agitator and fan and its guides. 30 Fig. 6 is a detail of its spring. Fig. 7 is a perspective detail of the detachable connection between the brush or head and its supporting shaft.

In the drawings the numeral 1 designates broadly the casing which is of box-shape having at about the center of its length an upright partition 2 rising nearly to its top 3 which is closed, and in rear of this partition a bottom 4 upon which moves a drawer 5 capable of being drawn out the rear end of the casing to dump the dust. Above the drawer is a longitudinal support 6 for an upright baffle 7 having through it holes 8, forward of this baffle another one numbered 45 9 depends from the top 3 and is also provided with holes 8, and in rear of the intermediate baffle 7 another baffle 10 depends from the top 3 but is by preference made solid; while the casing in rear of this solid baffle has holes 11 covered with muslin 12 so as to permit the escape of air but check or retain the dust within the casing 1. At the front end of the latter is a forwardly projecting nose 13 whose lower front end 50 carries rollers 14 which will travel upon the floor or pavement being swept, and in rear

of the nose and between it and the upright partition 2 is an opening for the fan yet to be described. Obviously this fan draws the dirt and dust upward and passes it over the upper edge of said partition 2 in rear of which it takes a tortuous course around the various baffles and through the holes 8, the air finally passing through the muslin 12 and out the holes 11 and the dust and particles of dirt falling into the drawer 5 whence it may be removed from time to time. 60

The support for the casing consists of a pair of traction wheels 15 fast upon a shaft 16 which extends through the casing just in rear of the partition 2; and from the sides of the casing rise handles 17 connected at their upper extremities by a cross bar 18 so that the device may be propelled forward by hand like an ordinary baby carriage. The wheels 15 have rubber tires 19 so that they will cling to the floor or pavement and will be caused to revolve as the device is propelled, although if their revolution is not desired the cross bar 18 is raised and the rollers 14 support the front end of the casing, but on the other hand, downward pressure on said cross bar forces the rubber tires more firmly onto the floor and 80 causes the positive rotation of the traction wheels as will be understood. 75

The fan best illustrated in Fig. 2 comprises propeller blades 20 whose hub 21 is fixed upon an upright shaft 22 which is 90 suitably mounted in the casing as shown, and it revolves within a circular opening 23 formed in the forward part of the casing in front of the partition 2 so that all air passing upward must pass through the fan and is thereby directed over the partition in the manner above mentioned. The opening 23 is disposed within an upright passage forward of said partition 2 and connects the upper front portion of the dust-receptacle 10 with the upper rear portion of the chamber beneath the nose 13. 95

The agitator is indicated at 30 as a brush head adapted to stir up or agitate the dirt upon the floor or pavement as it is rotated. 10 It is by preference circular and of a size to stand mostly under the nose 13 and to project a little under the fan as shown in Fig. 2. On its upper side it carries two ears 31 through which passes a pin 32 removably connecting it with an eye 33 at the lower end of a shaft 34 which extends upward through 11

the nose 13 and is journaled therein at 35, above which it rises in front of the casing 1 and passes through a bracket 36 which is mounted upon the front upper corner of the 5 casing 1 and has an upright portion 37 which carries a bolt 38. The latter engages a slot 39 in an L-shaped plate 40 whose upper end rests beneath the hub 41 of a gear wheel 42 by which the brush is driven. 10 Thus it will be seen that the brush head may be removed by withdrawing the pin, and some other form of agitating device substituted; also that by loosening the nut on the bolt 38 and adjusting the plate 40 the 15 height of the brush may be adjusted as desired, although it is intended that its bristles shall stand just a trifle below the rollers 14 as shown in Fig. 2.

The driving mechanism consists of a large 20 power wheel or gear 50 mounted fast upon the shaft 16 and engaging a driven wheel 51 which is fast on a counter shaft 52 journaled in a frame 53 which is carried by the casing 1, and the inner end of this counter shaft 25 has a beveled gear 54. The numeral 55 designates an upright shaft having a beveled gear 56 engaging that numbered 54, also having a horizontal driving gear 57 which engages a somewhat smaller and rather thick 30 gear 58 that is mounted loosely on the fan shaft 22 and in turn engages the gear 42 so as to drive the brush. The central gear wheel 58 is made rather thick so that the gear 42 which drives the brush may move 35 up and down thereon as necessary when the height of the brush is adjusted; and while said gear 58 is loose on the fan shaft 22, I connect it therewith by a backing ratchet 40 (whose description need not be elaborated) in order that when the device is being propelled forward the fan will be rotated in the proper direction to draw in air, but when the device is drawn to the rear the fan will still run forward under its 45 momentum but will not be driven in a reverse direction which would draw the dust undesirably out of the casing.

In use a stiff brush is applied if a pavement or coarse floor is to be swept, and a 50 finer brush if a finer floor is to be treated, and the same is adjusted at the proper height with respect to the rollers 14. The operator grasps the cross bar between the handles and propels the machine forward 55 over the floor or pavement, and the power set up by the clinging of the tires of the traction wheels 15 upon the floor or pavement, causes the driving gear 57 to rotate. The thick gear 58 is thereby caused to turn, 60 as also the gear 42 which through the shaft 34 drives the brush 30 constantly in the proper direction; and when the machine is being moved forward the thick gear through the ratchet 60 rotates the fan in the forward 65 direction, whereas the fan runs under its

momentum if the machine is drawn backward for a little distance, and at any rate will never be driven backward. The dust and dirt agitated by the brush is sucked upward by the fan and passed over the upper edge of the partition 2, whence it takes a tortuous course through and around the baffles 9 and 7 and against the baffle 10, from which it falls into the drawer 5 and is removed from time to time, the clear air passing out through the holes 11 and the muslin preventing the passage therethrough of the dust and dirt. If it be desired to pass over some obstruction, such as a door sill, the cross bar is depressed so that the rollers 14 and brush rise a trifle off the floor; on the other hand if it be desired to scrub or brush the floor very thoroughly, the brush is adjusted a little lower and then by raising the cross bar on the handles the bristles of the 75 brush will be forced downward onto the floor by the weight of the machine. The use of devices of this kind is obvious and I will not therefore elaborate further.

An amplification of my invention is also 80 illustrated in the drawings, and forms an important feature and by its use I am enabled to attach a suction nozzle or head. As best seen in Fig. 2, the support 6 above mentioned is made tubular, its front end opening through the upright partition 2 into 85 said passage and its rear end being threaded and closed by a removable cap 61, and when the latter is detached a hose 62 having a suction head or nozzle 63' can be attached as will 90 be clear, the form of the latter being immaterial. Within the passage beneath the fan 95 is a closure consisting of two fixed panels 66 and 66' spaced apart so as to leave an opening 70 between them, and a door 64 100 sliding on the guides 63 and adapted to be pushed over said opening so as to close it. One of the fixed panels has a spring 67 adapted to bear upward beneath the door 105 64 when the latter is closed. This is done 110 by grasping its handle 65 and shoving it in the direction of the arrow along the guides 63, so that the opening 70 is closed at a point beneath the fan; after which the rotation 115 of the latter creates suction through the tubular support 6 and hence through the hose 120 62 and nozzle 63'. At this time the brush will obviously be raised off the floor, and although it rotates it will perform no function. When the device is used as a vacuum 125 cleaner of this type, it is propelled along the floor by one hand while the operator holds the nozzle 63' in his other hand and moves it along the wall or furniture or holds it in contact with other articles to be cleaned 130 by the suction process, the air and dust taken in obviously flowing along the pipe 62, through the tubular support 6, upward through the fan, and thence into the drawer by the course above outlined.

What is claimed as new is:

1. In a cleaning machine, the combination with a casing having a transverse partition with a dust-receptacle in rear of it, a nose 5 extending forward from the casing and leaving the front portion of the bottom of the latter open, a rotary brush disposed within the open portion of said bottom, and an upright shaft to which the brush 10 is secured; of a fan located within the casing forward of said partition, an upright shaft on which it is fast, and means for rotating said shafts.
2. In a cleaning machine, the combination 15 with a casing having an upright transverse partition and its bottom closed in rear thereof, a dust-drawer above said bottom, the front portion of the bottom being open, and a brush within the open portion; of a rotary 20 fan within the casing forward of said partition, an upright shaft on which the fan is fixed, a wheel mounted loosely on said shaft, means for rotating the wheel in either 25 direction, a backing ratchet between said wheel and fan-shaft for the purpose described, and connections between the wheel and the brush.
3. In a cleaning machine, the combination 30 with a casing having a transverse partition with a dust-receptacle in rear of it, a nose extending forward from the casing and leaving the front portion of the bottom of the latter open, a rotary brush disposed within the open portion of said bottom, an upright 35 shaft to which the brush is secured, and a gear at the upper end of the shaft; of a fan located within the casing forward of said partition, an upright shaft on which it is fast, a thick gear loose on this shaft and in 40 constant mesh with the gear on the brush-shaft, means for rotating the thick gear in either direction, and a backing ratchet between this gear and the fan shaft.
4. In a cleaning machine, the combination 45 with a casing, a dust-receptacle in its rear portion, and a nose projecting forward from the front of the casing; of a brush disposed beneath said nose, an upright shaft journaled through said nose and connected at its 50 lower end with said brush, a bracket on the casing in which said shaft is journaled, a bolt in this bracket, a gear fast on the upper end of the shaft, an L-shaped plate whereof one member surrounds the shaft beneath the 55 hub of the gear and the other is provided with a slot in which said bolt is adjustable, and means for driving said gear.
5. In a cleaning machine, the combination 60 with a casing, a dust-receptacle in its rear

portion, a rotary fan disposed in its front 60 portion, and a nose projecting forward from the front of the casing; of a brush disposed beneath said nose, an upright shaft journaled through said nose and connected at its lower end with said brush, a bracket on the 65 casing in which said shaft is journaled, a bolt in this bracket, a gear fast on the upper end of the shaft, an L-shaped plate whereof one member surrounds the shaft beneath the hub of the gear and the other is provided 70 with a vertical slot in which said bolt is adjustable, a gear on the fan shaft meshing with the gear on the brush-shaft, and means for driving one of said gears.

6. In a cleaning machine, the combination 75 with a casing, a dust-receptacle in its rear portion, a rotary fan disposed in its front portion, and a nose projecting forward from the front of the casing; of a brush disposed beneath said nose, an upright shaft journaled through said nose and connected at its lower end with said brush, a bracket on the 80 casing in which said shaft is journaled, a bolt in this bracket, a gear fast on the upper end of the shaft, an L-shaped plate whereof one member surrounds the shaft beneath the hub of the gear and the other is provided 85 with a slot in which said bolt is adjustable, a thick gear on the fan-shaft engaging the gear on the brush-shaft, a backing ratchet 90 connecting said thick gear with the fan-shaft, and a driving gear engaging the thick gear.

7. In a machine of the class described, the combination with a casing mounted on 95 wheels and having a nose at its front portion opening downwardly and a dust receptacle at its rear portion, a brush disposed within said nose, connections between it and said wheels for driving the brush whichever 100 way the machine is propelled, a fan disposed between said receptacle and brush, and connections between it and said wheels for rotating the fan when the machine is propelled in one direction only; of a closure 105 between the fan and brush, and a tube communicating with the space between the fan and closure and leading to the exterior of the casing where it is adapted to be closed or to receive a suction nozzle. 110

In testimony whereof I have hereunto set my hand in presence of two subscribing witnesses.

WILLIAM T. SHAFFER.
